US00D923692S

(12) **United States Design Patent** (10) **Patent No.:** **US D923,692 S**
(45) **Date of Patent:** **** Jun. 29, 2021**

(54) **AUDIO EYEGLASSES**

(71) Applicant: **Bose Corporation**, Framingham, MA (US)

(72) Inventors: **Seth N. Green**, Framingham, MA (US); **Matthew Storey**, Austin, TX (US)

(73) Assignee: **BOSE CORPORATION**, Framingham, MA (US)

(**) Term: **15 Years**

(21) Appl. No.: **29/718,148**

(22) Filed: **Dec. 20, 2019**

(51) **LOC (13) Cl.** **16-06**

(52) **U.S. Cl.**

USPC **D16/309**

(58) **Field of Classification Search**

USPC 351/43, 44-47, 49, 59, 63, 69, 104, 123, 351/126, 131, 132, 135, 145; D16/101, D16/300-342; D29/108-110; D14/372

(57) **CLAIM**

The ornamental design for audio eyeglasses, as shown and described.

DESCRIPTION

FIG. 1 is a perspective view of a audio eyeglasses as seen from the front, top, and right side;

FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

1 Claim, 5 Drawing Sheets
